ATTORNEY.

UNITED STATES PATENT OFFICE.

ARTHUR BEASLEY, OF EAST ST. LOUIS, ILLINOIS.

EQUALIZING JOURNAL-BOX.

1,306,460.

Specification of Letters Patent. Patented June 10, 1919.

Application filed April 23, 1917. Serial No. 164,041.

To all whom it may concern:

Be it known that I, ARTHUR BEASLEY, a citizen of the United States, and a resident of East St. Louis, Illinois, have invented 5 certain new and useful Improvements in Equalizing Journal-Boxes, of which the following is a specification containing a full, clear, and exact description, reference being had to the accompanying drawings, forming 10 a part hereof.

My invention relates to an improved equalizing journal-box for car trucks, and consists in the novel construction and combination of parts hereinafter described and 15 particularly pointed out in the claim found at the end of this specification.

Heretofore, much trouble and delay has been caused by "hot boxes" during the operation of trains and cars, and I have discovered that in a great many cases the trouble is 20 caused by unequal distribution of the weight of the load upon the car-axle journals and bearings.

The object of my invention is to provide 25 an improved means whereby the weight of the load will be imposed equally at both ends of the journals and their bearings or "brasses," and thus prevent friction and its consequential overheating and undue wear 30 and cutting of the journals and brasses.

In the drawings,

Figure 1 is a side-elevation, partly in section, of a car-truck side frame and its journal-boxes, having my invention applied 35 thereto, and

Fig. 2 is a transverse section, taken on the line 2—2 of Fig. 1.

The numeral 1 designates a car-truck side-frame, which may be of the usual construction except as to the points hereinafter 40 particularly described and claimed.

The numerals 2, 3, indicate the usual car-wheels and axles, respectively.

The journal-boxes 4 are of the usual construction, except that they each are provided with a transverse semi-circular bearing recess 5 upon their upper portions, the said bearing being located, in the present illustration of my invention, upon the exterior of the boxes; 45 and the bearing 5 is engaged by a cylindrical journal 6 formed integral with and extending longitudinally of the side-frame 1, whereby the boxes and side-frame will be hingedly or pivotally connected, and permit the said 50 boxes to rock freely, without any corresponding movement of the frame, and there-

by relieving the journals 7 of the axles 3, as well as the brasses 8, of undue strain when the said axles and journals move up and down at alternate ends (as they do) when 60 the car is running upon a rough or uneven track.

The said journal-boxes 4 are loosely mounted in the jaws of the pedestals 8, and a common bolt 9 extends across the bottom of 65 said boxes 4 and connects the lower portions of said jaws below said boxes, to prevent the boxes from being accidentally separated from said pedestals, as well as to strengthen said jaws. It will be observed that the said 70 semi-circular bearing recess 5, as well as the cylindrical journal 6, extends completely across the top of the journal-box 4; thus providing a very long-wearing bearing 75 thereat, which occupies the entire space between the upper ends of the spaced-apart jaws of said pedestals 8, such a construction being made possible by the fact that the emergency means (to prevent separation of the side-frame and journal-box) is located at 80 the lower ends of said pedestal jaws, in the form of the said bolt 9 extending across the space between said jaws, below, and entirely underneath the journal-box, as previously described.

The numeral 10 designates the brass or bearing, which rests upon said journal 7, and 11 indicates the usual wedge which rests upon said brass.

The operation is as follows: 90
When the car carrying the side-frame and boxes, arranged as described, in accordance with my invention, runs over a rough or uneven track, the journals 7 of the axles 3 will be alternately moved up and down; but no 90 undue strain will be thrown upon said side-frame, or the journals, nor upon the brass 10, because said side-frame and said boxes are in "loose" relation to each other, and in fact are (in the present showing) "pivotally" connected; which construction will effectually prevent undue "warping" or twisting of said side-frame (and possible breakage thereof at its weakest point, near the lower end of the columns, or elsewhere), as 100 well as preventing undue strains being thrown upon said journal, the brass and displacing the dust-band and the lubricating substance within the box.

In boxes which are not fitted with my invention the dust-band is moved up and down with the journal, and the wedge and lubri-

cating substance are often displaced, the oiled waste being forced away from the inner end of the journal and box, leaving the journal and brass dry, and causing heating 5 and cutting, and possible breakage of the journal.

I do not limit myself to the exact form of parts herein shown and described, as it is clear that many changes may be made by 10 skilled workmen without departing from the spirit and scope of my invention.

I claim:

In a car-truck, a side-frame having spaced 15 pedestal-jaws; a bearing which permits an unlimited rocking movement of said side-frame on the journal-boxes thereof; journal-

boxes which are devoid of the usual side-flanges, whereby said boxes have an unlimited rocking movement beneath said side-frame; and an emergency means for preventing the accidental separation of said side-frame and said boxes, and which means will not interfere with the free rocking movement of the side-frame relative to said boxes. 20

In testimony whereof I have signed my name to this specification, in presence of two subscribing witnesses.

ARTHUR BEASLEY.

Witnesses:
